UNITED STATES PATENT OFFICE.

ANTON HOVORKA, OF CHICAGO, ILLINOIS.

BOX-FASTENER.

1,089,708.

Specification of Letters Patent. Patented Mar. 10, 1914.

Application filed June 17, 1913. Serial No. 774,231.

To all whom it may concern:

Be it known that I, ANTON HOVORKA, a citizen of the United States, residing at Chicago, in the county of Cook and State 5 of Illinois, have invented certain new and useful Improvements in Box-Fasteners, of which the following is a specification.

This invention relates to improvements in devices for fastening down the lid of crates 10 and other boxes, and its object is to provide a simple and efficient fastening which will securely hold the lid closed, said fastening being constructed to permit the application of a seal or pad-lock.

15 In order that the invention may be better understood, reference is had to the accompanying drawings, in which—

Figure 1 is a perspective view of a crate equipped with the fastening device. Fig. 20 2 is a cross section of the crate on the line 2—2 of Fig. 1. Fig. 3 is a perspective view of the fastening member. Fig. 4 is a perspective view of the keeper for the fastening member. Fig. 5 is a section on the line 25 5—5 of Fig. 2.

Referring specifically to the drawings, the walls of the crate are solid panels assembled and fastened together in any suitable manner. The panel forming the front wall 30 of the crate is constructed of boards 5 nailed or stapled to top and bottom strips 6 and 7, respectively, extending throughout the entire length of the panel, said strips being on the outer face of the panel. The crate has a 35 hinged lid composed of boards or strips 8 nailed or stapled to front and rear strips 9 and 10, respectively, extending throughout the entire length of the lid, said strips being on the top of the boards. Midway between 40 its ends, the front strip 9 is cut away at its front edge to form a recess 11, and on the top surface of the board 8, exposed by said recess, is mounted a metal plate 12 having an upward bend 13 at one end to engage the 45 rear edge of the strip, and a downward bend 14 at the opposite end to engage the front edge of said board. The plate 12 has an up- 50 standing ear 15 provided with a perforation 16. The ear may be struck up from the plate.

55 Between the top strip 6 and the middle board 5 of the front wall of the crate is mounted a stem 17 having lateral bends 18 and 19, respectively, at its ends, said bends being in opposite directions and forming 55 hooks. The faces of the parts 5 and 6 may

be grooved to form a seat for the stem, the latter being rotatable for a purpose to be presently described. In the strip 6 is an aperture 20 into which the bend 18 extends. To fasten the lid down, the stem 60 17 is rotated until the bend 19 extends across the top of the plate 12 alongside the ear 15. The bend 19 has an aperture 21 which registers with the perforation 16 when the parts are in this position, so that 65 a seal or shackle of a padlock may be passed through the registering aperture and perforation to lock the lid.

On one side of the ear 15 the plate 12 has a protuberance or upward bulge 22 over 70 which the part 19 must be snapped before it comes alongside the tongue. This will hold the part 19 from swinging back off the plate 12, if a seal or padlock is not used, and the lid will be securely held closed. The 75 lid can be easily released by simply swinging the part 19 back sufficiently to clear the plate 12. The bend 19 is resilient, so that it may be snapped over the bulge 22 as described. 80

Two small triangular tongues 23 are punched downward out of the plate 12, and when said plate is mounted on the board 8, the tongues are driven into said board, whereby an additional fastening means for 85 the plate is provided, and rattling and loosening of the same is prevented.

I claim:

A box having a hinged lid, a strip extending lengthwise across the forward portion of the lid and having its front edge recessed, a plate mounted on the lid beneath the recess of the strip, said plate having bends in opposite directions at its end, one of which bends engages the front edge of 90 the lid, and the other bend the rear edge of the strip, an upstanding perforated ear on the plate, and a stem carried by the box wall and having a lateral bend, said stem being rotatable to locate the bend across the 95 plate alongside the ear, the bend having an aperture to register with the perforation of the ear. 100

In testimony whereof I affix my signature in presence of two witnesses.

ANTON HOVORKA.
